MULTIPLE STAGE VACUUM TUBE

Chris S. Andersen, Bell, Calif.

Application January 28, 1941, Serial No. 376,289

7 Claims. (Cl. 250—27.5)

My invention relates to grid controlled vacuum tubes and more particularly to a means of supporting the elements of an electronic tube in such a manner that a plurality of stages or individual electrode assemblies may be mounted within the same envelope.

Among the objects of my invention are:

To provide means for rigidly supporting electrodes in such a manner that a plurality of individual units may be enclosed in a single envelope; to provide a means and method of energizing a plurality of symmetrically disposed electrode assemblies from a single cathode; to provide a plurality of electrodes for a multistage electron discharge tube which can be assembled at minimum cost; to provide a means and method of supporting, and electrically operating a plurality of electrode assemblies in a single envelope; to provide a small, compact multistage tube ideally adapted for use in hearing aids and similar low weight devices; and to provide a simple and efficient multistage vacuum tube.

Other objects of my invention will be apparent or will be specifically pointed out in the description forming a part of this specification, but I do not limit myself to the embodiment of the invention herein described, as various forms may be adopted within the scope of the claims.

In the drawings Fig. 1 is a view partly in section, and partly in elevation of one form of my invention, having three stages therein. Figs. 2, 3, 4, and 5 are views partly in section and partly in elevation taken as indicated by the lines 2—2, 3—3, 4—4, and 5—5, respectively, in Fig. 1. Fig. 6 is a wiring diagram showing how a six-stage tube made in accordance with my invention may be energized as an efficient multistage amplifier.

Referring to the drawings for a more detailed description of my invention, an envelope 1 is provided at one end thereof with a stem 2 closed at the top by the customary press 3 through which lead-in wires are passed and the supporting elements are embedded. The main support of electrodes comprises a pair of relatively heavy support rods 5 extending upwardly from the press, these support rods being provided with lead-in wires 6. Individual electrode assemblies are mounted on support rods 5 and may be assembled from the top.

First to pass over the rods is a lower mica washer 7 having a central aperture 9 therein, the rods passing through peripheral apertures in the washer, and supported on beads 10. Immediately over the mica washer 7 is positioned

a ceramic disc 11, this disc having a central aperture 12 and a counterbore 13. The aperture 9 in mica disc 7 is smaller than the aperture 12 in the ceramic disc 11, and a grid 14 in the form of a spiral having the end turns thereof closer together than the intermediate turns, is dropped into central aperture 12 in ceramic disc 11 with the end turns filling the aperture. A cylindrical anode 15, either solid as shown, or mesh 10 screen, has one end thereof inserted into counterbore 13, this anode being shorter than the length of grid 14. A second ceramic disc 16, similarly bored and counterbored to disc 11 is then inverted over the grid-anode assembly, being held against gravity by resting on the upper edges of both anode and grid. A mica washer 7' is then dropped over the rods 5, this washer having an aperture 9' similar to washer 7. The assembly may then be continued upwardly with grid 14' and anode 15' held by the discs 11' and 16'. A third washer 7'' may then be added and a third stage comprising grid 14'' and anode 15'' held by the discs 11'' and 16''. A top washer 7''' is then used to cap the electrode assembly. The assembly may be held in place by top beads 20 on top of washer 7''' and if desired, additional rods 21 may be added, passing through all washers at the periphery thereof 90° from rods 5. These rods may be used as connections from various electrodes.

It will be seen that in the serial assembly of washers, discs, and electrodes, as described, an axially clear space is left through which a filament 22 may be passed, without touching any of the tube structures. At the lower end the filament 22 is welded to bar 24 attached to one rod 5, and at the upper end filament 22 is attached to filament spring 25 which is formed with a recurved portion 26 to which the upper end of 40 the filament is attached. Filament tension can be easily adjusted and the filament may be accurately centered with such a recurved spring.

All connections to grids and anodes are brought out separately through the press, and I prefer to attach connections 21, 27' and 27'' to the anodes on the exterior thereof, between the ceramic discs, and bring them downwardly to meet the lead wires. For example, the upper anode 15'' may be connected by wire 27'' to one of rods 21. The upper grid 14'' may be connected by wire 28'' passing between disc 11'' and washer 7'' to opposite rod 21. Anode wire 27' may be brought out laterally and then downwardly through apertures 30 in washers 7 and 7'. The wire 29' to grid 14' is connected to the lower end of the grid

and is brought out between the adjacent ceramic disc and mica washer to the edge of the mica washer and is then passed downwardly through grid wire apertures 32 in the various mica washers. Grid 14 may be connected through wire 28 passing between washer 7 and disc 11, thence to a lead-in wire through an aperture 31 in disc 7. Thus the anode and grid wires are well separated and preferably run to opposite sides of the various mica washers to reduce capacity effects.

After the assembly of as many stages as desired is accomplished, the tube may be pumped and sealed in the customary manner, through the exhaust tip 35 at the top of the tube. Obviously, however, other positions of the exhaust tip may be provided, as is well known in the art.

I have found that tubes made in the manner just above described may be quickly and easily assembled to provide substantially as many stages as may be desired and in an extremely small space. For example, I have made a four-stage tube in this manner, which is only half an inch in diameter and an inch and a half long, and a six-stage tube is very little longer. Such a tube is ideally adapted for use in hearing aids where weight and space are at a premium.

I should like to point out, however, that it is not necessary that all stages of the tube of my invention have the same characteristics. While I have shown all grids and anodes in Fig. 1 as being identical, it will be obvious that each individual stage may be designed to have different and desirable characteristics, as is well known in the art.

In Fig. 6 I have shown one circuit which is ideally adapted for use with a six-stage amplifier tube built according to the design of Fig. 1 with, however, the different stages slightly changed to provide the desired results. In this case an input device 40, such as a crystal microphone, is coupled to first stage 41 through a capacity 42. In Fig. 6 I have shown each stage as a conventional triode but it should be fully understood that all of these stages are contained within the same envelope. Grid 44 of stage 41 is maintained positive with respect to its cathode portion 45 through resistor 46 energized by battery 47 through grid supply line 49. The anode 50 of stage 41 is also positively energized through resistor 51. The plate impedance of this stage is very high and the anode 50 thereof is coupled to grid 52 of the second stage 54 through capacity 55. Inasmuch as the impedance of stage 54 must also be high, grid 52 thereof is biased through variable resistor 56 to bias line 57 which connects through resistor 59 to one side of input device 40, thus making the grid having a bias common to the cathode or filament. The amplification of stage 54 is low, allowing high grid impedance. Stage 60 is a duplicate of stage 41 and preferably has a high amplification factor. Stage 61 is a low amplification stage and therefore it is biased similarly to stage 54. Its purpose is to invert the signal without any amplification, which may be accomplished by making resistor 64 of low resistance. The signal is then delivered to stage 65 which has a medium amplification factor and acts as one-half of the output stage. Stage 66 is the other half of the output stage and is energized through line 67 from stage 60. Thus the output stage can be class B, stage 60, or stage 61, acting through 180° of the signal. The output voltage will be greater than with a single stage output, and potentials can be provided through resistors 69 to the output stage so that a

crystal output device 70 for example, can be connected directly to the anodes of stages 65 and 66 without constant potential appearing on the output device. The advantage of such an output arrangement is to generate a large signal with a small anode voltage, thus making the circuit ideally adapted for use in hearing aids, for example. The cathode 45 is energized through a cathode battery 71 under control of a cathode switch 72.

Thus I have described a multiple stage vacuum tube that can be easily assembled in a very small envelope and which can be used in multi-stage form with relatively low potentials, to provide a compact, efficient tube and circuit for use where weight and space are at a premium, such as in hearing aids.

I claim:

1. In a multi-stage vacuum tube having an envelope and a press supporting upright parallel main support rods, an electrode assembly comprising a thin refractory washer mounted on said rod, a ceramic disc on said washer inside of said rods, said washer and said disc having coaxial bores therein, and said disc having an additional counter-bore, a grid having end turns spaced closer than intermediate turns thereof mounted with said end turns fitting the bore of said disc with the end of said grid resting on said washer, an anode mounted to fit in said disc counter-bore, a second disc positioned inside of said rod and inverted over said grid and anode, said second disc having a central bore coaxial with the bore of said first disc, said second disc having first and second counter-bores, said first counter-bore fitting the opposite closer end turns of said grid, and said second counter-bore fitting the opposite end of said anode, said opposed discs forming the sole positioning and supporting means for said grid and anode, a second centrally bored washer positioned over said second disc and mounted on said rod, and means for preventing said second washer from moving along said rod, said second washer thereby holding said assembly in place, and a filament passing through said discs, washers and grid.

2. In a multistage vacuum tube having an envelope and a press supporting upright parallel main support rods, an electrode assembly comprising a thin refractory washer mounted on said rods, a ceramic disc on said washer, said washer and said disc having coaxial bores therein and said disc having in addition a counter-bore, a grid having end turns spaced closer than intermediate turns thereof, mounted in the bore of said disc and resting on said washer, an anode mounted in said disc counterbore, a similar disc and washer inverted over said grid and anode, means on said rod to position said washers, and a filament passing through said discs, washers and grid.

3. A tube in accordance with claim 1 wherein a lead to said anode is brought out between said discs and a lead to said grid is brought out between a disc and a washer.

4. A tube in accordance with claim 1 wherein a lead to said anode is brought out between said discs and a lead to said grid is brought out between a disc and a washer, said leads being brought out in opposite directions.

5. A tube in accordance with claim 1 wherein a lead to said anode is brought out between said discs and a lead to said grid is brought out between a disc and a washer, said leads being

brought out in opposite directions, and short support rods spaced 90° from said main support rods and passing through both of said washers.

6. A tube in accordance with claim 1 wherein said filament is connected at each end to a main support rod.

7. A tube in accordance with claim 1 wherein

a plurality of superimposed units are assembled on said main rods, with the top washer of one unit acting as the lower washer of the unit above, with said filament passing axially through all of said units.

CHRIS S. ANDERSEN.
